UNITED STATES PATENT OFFICE

HARRY COHN, OF BROOKLYN, NEW YORK

DESIGN FOR A STORE FRONT

Application filed September 27, 1932. Serial No. 45,082. Term of patent 7 years.

To all whom it may concern:

Be it known that I, HARRY COHN, a citizen of the United States, residing at Brooklyn, county of Kings, and State of New York, have invented a new, original, and ornamental Design for a Store Front, of which the following is a specification, reference being had to the accompanying drawing, forming part thereof.

Figure 1 of the drawing is a front view of the store front embodying the present invention, and Fig. 2 is a top plan view of such store front.

The dominant feature of the present invention resides in a store front, the front of which simulates in appearance a pair of spectacles.

I claim:

The ornamental design for a store front, substantially as shown and described.

HARRY COHN.
